By J. M. Cooke,
Attorney.

UNITED STATES PATENT OFFICE.

JOHN JACOB KINZER, OF WILDWOOD, PENNSYLVANIA, ASSIGNOR TO PITTSBURG BRAKE SHOE COMPANY, OF PITTSBURGH, PENNSYLVANIA, A CORPORATION OF PENNSYLVANIA.

BRAKE-SHOE.

1,057,849.

Specification of Letters Patent.

Patented Apr. 1, 1913.

Application filed September 10, 1912. Serial No. 719,553.

To all whom it may concern:

Be it known that I, JOHN JACOB KINZER, a resident of Wildwood, in the county of Allegheny and State of Pennsylvania, have 5 invented a new and useful Improvement in Brake-Shoes; and I do hereby declare the following to be a full, clear, and exact description thereof.

My invention relates to brake-shoes, and 10 has special reference to the class of brake-shoes for railroad car and other like wheels which have an inclosing casing provided with a filling of frictional material therein.

The object of my invention is to provide a 15 cheap, simple and efficient form of brake-shoe of this class which can be firmly held in engagement with the tread of the wheel when desired and along the entire face of the shoe, as well as be one in which the 20 shoe will be greatly strengthened in order to prevent any buckling, turning or curving of the shoe when in use and thereby enable the same to hold its original shape.

To these ends my invention consists, generally stated, in the novel arrangement, construction and combination of parts as hereinafter more specifically set forth and described and particularly pointed out in the 25 claims.

30 To enable others skilled in the art to which my invention appertains to construct and use my improved brake-shoe, I will describe the same more fully, referring to the accompany drawing, in which—

35 Figure 1 is a back plan view of my improved brake-shoe. Fig. 2 is a longitudinal section of the shoe on line 2—2 Fig. 1. Fig. 3 is an end view of the same. Fig. 4 is a cross-section on the line 4—4 Fig. 1.

40 Like symbols of reference herein indicate like parts in each of the figures of the drawing. As illustrated in the drawing, 1 represents my improved brake-shoe, which comprises an inclosing casing 2 and a filling 45 *a* of frictional material inserted within said casing. The casing 2 is preferably formed from refractory material, sheet, plate or other metal having a substantial degree of strength and ductility, such as 50 malleable, wrought or other steel or iron, and when formed from refractory material, sheet or plate metal it is pressed or bent in suitable dies into a structure having an integral back-wall 3, side walls 4 and end 55 walls 5, as well as being open at its front

for the insertion of the filling material *a* and curved substantially in accordance with the periphery of the car wheel on which the brake-shoe is to be used.

In the formation of the casing 2, as above 60 described, the back 3 is bent or struck out where it connects with one of the sides 4 to form the raised flanged portion 6 on said casing and it is preferably rounded or curved from said back to said side. The 65 ends 5 of the casing 2 are each cut away, as at 7, in line with the raised portion 6 on the back 3 in order to form an opening in the shoe 1 for the flange on the wheel, as hereinafter described, and such opening 7 preferably conforms to the shape of said raised portion at its inner end by having such end rounded or curved as at 8, while its outer side conforms substantially to the side wall 4 adjacent to the same and 75 its inner side substantially to the opposite side wall 4 and curved, as at 9, in its connection with the inner edge of the end walls 5.

The usual supporting lug 10 is connected or fixed to the back 3 of the casing 2 in 80 any suitable manner, for connecting the shoe 1 to the ordinary approved shoe head or hanger (not shown), by having the inner ends 12 on its legs 11 passed through slots 3' in said back and turned against the inner face of such back to connect such lug to said casing.

A short bearing surface 13 is formed on the back wall 3 of the casing 2 and adjoining each of its ends which surfaces are adapted to abut against bearings on the ends of the brake-head or hanger, and such surfaces are preferably formed integral with such back by being bent or struck out of the back, while such surfaces are also preferably recessed as at 14. Central or intermediate bearing surfaces on the brake-head or hanger are adapted to abut against the back wall 3 on the casing and on each side of the lug 10, as at 15', and a central bearing surface 15 is preferably formed integral with said back wall and bent or struck out from the same for fitting within said lug to support and prevent said lug from being sheared off by the thrust of the hanger in the frictional pull of the shoe.

The back wall 3 of the casing 2 is preferably provided with a series of corrugations 16, which extend across said wall and are preferably formed by the material of said

back being bent or struck out, such corrugations extending between the bearing surfaces 13 and 15 and being preferably triangular in shape, as at 17. The raised flanged portion 6 on the back wall 3 of the casing 2 is also preferably corrugated across the same, as at 19, as well as the adjacent and opposite side wall 4 of said casing, as at 20, and preferably formed in like manner 5 as the corrugations 16 on said back wall. 10 The rubbing or frictional action of the brake-shoe 1 upon the tread *b'* of the wheel *b* is produced by the frictional member *a*, which consists of a filling of any suitable 15 material, such as a composition of matter specially prepared for the purpose, and of such a character as to exert proper and sufficient friction upon the periphery *c* of said wheel without the imposition of 20 undue or excessive pressure thereon, and compositions of this character are well known in the art. This filling *a* is either cast into the casing 2 or inserted in such casing under pressure and retained in position, after hardening, by the walls 3, 4 and 5, with portions of such material preferably entering the recesses 21 formed on the inner face of the back wall 3, raised portions 6 and side walls 4, by the corrugations 25 16, 19 and 20, respectively therein and by the bearing surfaces 13 and 15 in said back, while the side walls 4 and end walls 5 are preferably bent in by their corrugations and by bent portion, as at 5', respectively, to form a dovetailed connection with 30 said filling material *a* in the casing 2. The material *a* is also recessed in any suitable manner along the same, as at 22 and in line with the opening 7 and covered portion 8 35 in the end walls 5 which will form a hooked portion with the raised portion 6 in order to conform to and permit the flange *d'* of the wheel *b* to fit therein and hold the shoe in place in said wheel. 40 It will thus be seen that my improved 45 brake-shoe will provide for a clamping action between the same and the wheel flange which will act to hold said shoe in its proper position on the wheel's periphery and thereby permit the whole force of the friction member of the shoe to engage such periphery and enable the rounded or curved portion 50 between the recess in the raised portion and face of the shoe to fit or engage the corner or connection between the wheel flange and tread of the wheel. It will also 55 be seen that when my improved brake-shoe is in use the corrugations in the back, raised back portions and sides of the same will 60 greatly stiffen and straighten the shoe, so as to prevent any buckling, turning or curving out of the shoe at any point, which will not only add to the wearing qualities of the shoe but will greatly increase the braking power, while at the same time very 65

little, if anything, will be added to its cost of manufacture, and the holding power of the casing with the filling material greatly increased, while such corrugations in the casing will enable a lighter casing to be used than ordinarily and thereby greatly reduce the weight of the shoe and yet at the same time get better results by taking the dead weight off the brake beam and hanger. 70

Various modifications and changes in the design and construction of my improved brake-shoe may be resorted to without departing from the spirit of the invention or sacrificing any of its advantages. 75

What I claim as my invention and desire to secure by Letters-Patent is:— 80

1. A brake-shoe comprising an inclosing casing of pressed metal and a filling of frictional material, said casing and filling having hooked means on one side of the same for fitting over the flange of the wheel, and corrugations on the casing of said means. 85

2. A brake-shoe comprising an inclosing casing of pressed metal and a filling of frictional material, said casing and filling having a raised portion at one side of the same to form hooked means over the flange of the wheel, and corrugations on the casing of said raised portion and extending across the same. 90

3. A brake shoe comprising an inclosing casing of pressed metal and a filling of frictional material, said casing having a hooked portion at one side of the same for fitting over the flange of the wheel and formed by a raised portion on the back of said casing and a recessed portion in said filling, and corrugations on said hooked portion and extending across the same. 95 100

4. A brake-shoe comprising an inclosing casing of pressed metal and a filling of frictional material, said casing having a hooked portion at one side of the same for fitting over the flange of the wheel and formed by a raised portion on the back of said casing and a recessed portion in said filling, a curved portion on the end of said casing and filling material and connecting with said recessed portion to conform to the shape of the wheel between its flange and tread, and corrugations on the casing of said raised portion and extending across the same. 110 115

5. A brake shoe comprising an inclosing casing of pressed metal and a filling of frictional material, said casing and filling having hooked means at one side of the same for fitting over the flange of the wheel, and corrugations on the back of said casing and extending across the same. 120

6. A brake-shoe comprising an inclosing casing of pressed metal and a filling of frictional material, said casing and filling having a raised portion at one side of the same to form hooked means over the flange of the 125 130

- wheel, and corrugations on the back of said casing and extending across the same.
7. A brake-shoe comprising an inclosing casing of pressed metal and a filling of frictional material, said casing having a hooked portion at one side of the same for fitting over the flange of the wheel and formed by a raised portion on the back of said casing and a recessed portion in said filling, and corrugations on the back of said casing and extending across the same.
8. A brake-shoe comprising an inclosing casing of pressed metal and a filling of frictional material, said casing having a hooked portion at one side of the same for fitting over the flange of the wheel and formed by a raised portion on the back of said casing and a recessed portion in said filling, and angular corrugations on the back of said casing and extending across the same.
- 15 9. A brake-shoe comprising an inclosing casing of pressed metal and a filling of frictional material, said casing having a hooked portion at one side of the same for fitting over the flange of the wheel and formed by a raised portion on the back of said casing and a recessed portion in said filling, a curved portion on the end of said casing and filling material and connecting with said recessed portion to conform to the shape of the wheel between its flange and tread, and corrugations on the back of said casing and extending across the same.
- 20 10. A brake-shoe comprising an inclosing casing of pressed metal and a filling of frictional material, said casing having a hooked portion at one side of the same for fitting over the flange of the wheel and formed by a raised portion on the back of said casing and a recessed portion in said filling, a curved portion on the end of said casing and filling material and connecting with said recessed portion to conform to the shape of the wheel between its flange and tread, and angular corrugations on the back of said casing and extending across the same.
- 25 11. A brake-shoe comprising an inclosing casing of pressed metal and a filling of frictional material, said casing having a hooked portion at one side of the same for fitting over the flange of the wheel and formed by a raised portion on the back of said casing and a recessed portion in said filling, a curved portion on the end of said casing and filling material and connecting with said recessed portion to conform to the shape of the wheel between its flange and tread, and angular corrugations on the back of said casing and extending across the same.
- 30 12. A brake-shoe comprising an inclosing casing of pressed metal and a filling of frictional material, said casing having a hooked portion at one side of the same for fitting over the flange of the wheel and formed by a raised portion on the back of said casing and a recessed portion in said filling, a curved portion on the end of said casing and filling material and connecting with said recessed portion to conform to the shape of the wheel between its flange and tread, and angular corrugations on the back of said casing and extending across the same.

In testimony whereof, I the said JOHN JACOB KINZER have hereunto set my hand.

JOHN JACOB KINZER.
